Primary Examiner — Cynthia Ramirez*Assistant Examiner* — Gino Colan(74) *Attorney, Agent, or Firm* — Booth Udall Fuller, PLC(57) **CLAIM**

The ornamental design for a recess mount jamb, as shown and described.

DESCRIPTION

FIG. 1 is a perspective view of a recess mount jamb showing my new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is a front elevational view thereof; and,

FIG. 7 is a rear elevational view thereof.

The broken lines shown in the figures are included for the purpose of illustrating portions of the recess mount jamb and form no part of the claimed design.
